CABINET FOR ELECTRONIC EQUIPMENT

James J. La Due and Joseph F. Talerico, Poughkeepsie,
and William F. Dalton, Fishkill, N.Y., assignors to International
Business Machines Corporation, New York,
N.Y., a corporation of New York

Application March 16, 1959, Serial No. 54,998

Term of patent 14 years

(Cl. D26—5)

FIG. 1

FIG. 2

Fig. 1 is a front perspective view of a cabinet for electronic equipment, showing our new design; and

Fig. 2 is a rear perspective view thereof. The top, not shown, is conventional.

We claim:

The ornamental design for a cabinet for electronic equipment, as shown and described.
